UNITED STATES PATENT OFFICE.

CARL W. SWANSON, OF CHICAGO, ILLINOIS.

GEARING.

1,156,564.

Specification of Letters Patent. Patented Oct. 12, 1915.

Application filed March 8, 1912. Serial No. 682,401.

To all whom it may concern:

Be it known that I, CARL W. SWANSON, a citizen of the United States, residing at Chicago, in the county of Cook and State 5 of Illinois, have invented certain new and useful Improvements in Gearing, of which the following is a specification.

My invention relates to improvements in washing machines and has for its salient 10 object to improve the construction and arrangement of the operating and gearing parts of a washing machine whereby the clothes-containing receptacle shall be oscillated by means of a novel arrangement of 15 yielding power-transmission parts and whereby shifting of the power from oscillation of the receptacle to rotation of the wringer in either direction may be effected easily and with certainty.

Another object of my invention is to provide a machine which shall have the above 20 mentioned and other advantages and which shall at the same time be of simple, cheap, and durable construction throughout.

Other objects of my invention will become 25 readily apparent from a consideration of the following description taken in conjunction with the drawings, wherein; Figure 1 is an end elevation of a machine constructed in accordance with my invention; Fig. 2 is an elevation thereof from the opposite end; Fig. 3 is an enlarged vertical section on line 3—3 of Fig. 1 through the power-supplying clutch mechanism, with the latch 30 device shown in receptacle-engaging position; Fig. 4 is an enlarged section on line 4—4 of Fig. 2; Fig. 5 is a section of the yielding pitman, shown generally in Fig. 2; Fig. 6 is a section on line 6—6 of Fig. 1; 35 Figs. 7 and 8 are top views of the latch, shown respectively in position to permit oscillation of the receptacle and in receptacle-engaging position; Fig. 9 is an enlarged elevation of the wringer-reversing 40 mechanism shown at the top of Fig. 1; and Fig. 10 is a detail of the cam member of the wringer-reversing mechanism.

In the drawings, 15 and 16 indicate front and back frame strips or legs of stiff metallic construction, said strips at their lower ends bent to form feet 17. At each end of the frame, the strips converge toward each

other and are riveted together at their tops, as at 18, so forming an end frame structure of lambdoidal shape. The strips are connected near the bottom thereof by longitudinal and transverse braces 19—19 and 20—20 forming a horizontal generally-rectangular, base-frame. For additional strength I preferably run diagonal braces or struts 21 from a point 22 on the rear strip 16, across the frame ends, each extending just above the braces 19 and 20. The apices of the end frame structures are connected longitudinally by a wringer frame to be described. 60

The clothes containing receptacle 24, is constructed of sheet metal, and is suitably formed to perform its functions as a result of oscillation imparted thereto. At each end I secure to the receptacle a plate, each 70 of which provides a trunnion upon which the receptacle may be oscillated in the frame, and which may further provide the connections for the oscillating means and for the latch to be described. Specifically 75 26—26' indicate circular plates riveted to opposite ends of the receptacle and provided each with a trunnion 27 which rests on an appropriate block 28 secured on the front leg 15 of the proximate end frame. 80

I prefer that the power to oscillate the receptacle shall be applied thereto at a point remote from the axis of oscillation, in order that the strains of carrying heavy loads of clothing and water will not be imposed in 85 too localized a fashion upon the sheet metal ends immediately adjacent to the trunnion-carrying plate 26 and I further prefer that such power shall be applied to the receptacle from an oscillating member having 90 connection with the receptacle only through a spring which is laterally resilient in either direction. In the specific structure shown the trunnion plate 26 has an integral extension arm 30 suitably riveted to the end 95 wall of the receptacle and extending to a considerable distance from the center of oscillation, said arm at its extremity having an inturned ear 31 perforated for attachment of the power devices. Upon the trunnion 27 is loosely mounted a rocking lever 32, preferably having its power receiving arm 33 of yoke shape as shown in Fig. 4 for adequate bearing at two points upon the 100

trunnion 27, said lever having an extended power-applying arm 34 running forward in parallelism with the arm 30, said arm 34 preferably terminating at a considerable distance from the ear 31. Between the extremities of the two arms 31 and 34 I provide a spring connection preferably in the form of strong, laterally resilient coil spring 35 relatively stiff but capable of being bent 10 transversely to curve its axis in either direction, said spring being secured to the end heads 36, which are respectively secured in the ears 31 of the receptacle arm 30, and to a pin 37 carried by the vibrating arm 33. 15 This form of connection permits of spring-resisted lost motion between the receptacle and the vibrating lever, so that it is impossible to throw sudden strains and jars upon the receptacle from violent movements 20 of the vibrating arm and conversely momentum acquired by the receptacle cannot react suddenly on the vibrating arm.

The oscillating lever 32 is preferably operated from a drive shaft in the base of the 25 frame through the intermediary of a crank and pitman, and it is my preference that the pitman be made longitudinally yielding for extension and compression. In the drawings 38 indicates the power shaft mounted 30 in suitable bearings in the base frame end member 20, and carrying at its appropriate end a crank arm 39, connected by the pitman 40 to an appropriate arm 33 of lever 32. The pitman 40 preferably consists of a sleeve 35 member 41 and a stem member 42 telescoping therein, said stem member sliding through a bearing abutment 43 fixed within the tubular sleeve member 41 and said stem carrying above and below said abutment 43 40 heads 44—44 to receive the opposite ends of two springs 45 which extend toward and abut against the bearing 43. Manifestly 45 with the construction shown the pitman may be extended or compressed somewhat so that it acts as a shock absorber between the crank arm 39 and the rocking lever 32.

Of course the receptacle, when filled with clothes and water, attains considerable momentum that tends to prevent reversal of 50 the direction of movement, and so further to ease the action of the device in order that some resistance may be interposed to the movement of the receptacle to prevent it from accelerating the shaft action just before the crank reaches its dead center position 55 with respect to the pitman, and to ease the action of the machine at such reversing points when the crank is passing dead center, I preferably provide upon the crank 60 shaft a two point cam 47, to act against the leaf spring 48 of suitable rigidity and curvature secured in the base frame member 19.

For driving the machine, I provide an 65 electric motor 50 suitably mounted upon a base plate 51, suspended centrally of the

base frame, the shaft of said motor bearing a worm 52, meshing with the worm gear wheel 53 loosely mounted on the power shaft 38, said gear 53 having its hub extended in the form of a sleeve 54 which reaches substantially to the end frame of the machine 70 opposite to that on which the power transmitting connections are arranged. Both end surfaces of the hub of the gear 53 are formed into positive clutch members, the one clutch 75 member 55 coöperating with a sliding clutch member 56, splined upon the power shaft, and the opposite clutch member 57 of said gear-hub coöperating with the clutch surface 80 85 88 of a clutch member 59 which is slidable and rotatable upon the sleeve 54, and has at its opposite end teeth 60 constantly engaged with teeth 61 on the hub of a sprocket wheel 62 loosely mounted upon sleeve 54, and adapted for operating the clothes wringer to 95 be described.

The shipper arms 63 and 64 for the two clutch members 56 and 59, are secured in common upon a shipper bar 65, slidably mounted in suitable bearings in the frame 90 members 20 and connected at its outer ends as at 66 with a shipper lever 67 which is pivoted as at 68 at its lower end in a frame lug and extends up beside the machine to convenient operating position. Manifestly 95 by throwing the handle of the shipper lever 67 inward to its fullest extent the clutch 56 is disengaged from the gear wheel 53 and the clutch 59 is engaged with said gear wheel 53, so that the driving mechanism for the 100 clothes receptacle is not operated, but the driving gear 62 for the wringer is connected to the gear wheel 53 through said clutch 59. When said shipper lever is moved to the intermediate position shown in Fig. 3, both 105 the clutches 56 and 59 are thrown out of engagement with the worm gear 53 so that said gear turns idly on its shaft. When the lever 67 is moved to its outermost position the clutch 56 is engaged with the gear wheel 110 53, so that said gear may rotate the power shaft 38.

The shipper lever 67 works in a guide 69 carried by a bracket 70 secured to the leg 16 of the appropriate end frame, and in association therewith I provide a latching device 115 effectively coöperating with both the oscillating body and the shipper lever so that when the body is locked the shipper lever is also locked against movement to position to start the oscillating operation of the receptacle, thus insuring that the latch must be opened before the operation of the receptacle may be started. Thus upon the bracket 70 I provide a bearing structure 71 in which is mounted a rotatable latch member 72 having its axis of rotation arranged at an oblique angle to the end of the receptacle 24. On the inner end of the latch member 72 is a small crank arm 73 with a latch nose 74 120 125 130

projecting to its extremity so that when the latch member is rotated to one position shown in Fig. 8 said nose engages in a latching recess 75 formed in one of the bracing arms 76 of the plate 26'. When the latch is rotated to a diametrically opposite position the nose 74 is thrown completely out of the path of oscillation of said recessed arm 76. Upon the opposite end of the rotatable lock member I provide a finger lever 77 and at right angles thereto a guard stud 78, both of which are rotatable into or out of the path of movement of the shipper lever by the locking or unlocking movements respectively of the latch. The position of the projections 77 and 78 is such that they do not interfere with the movement of the shipper lever to its innermost (wringer-actuating) or central (neutral) position, but will positively prevent the movement of the shipper lever to its outer (receptacle-operating) position except when the latch is rotated to the position shown in Fig. 8, when its nose 74 is completely out of the path of the receptacle reinforcing arm 76. In this way positive provision is made for preventing the clutch being thrown to connect the power shaft to the motor while the latch is in locking position. The latch is so arranged in relation to its recessed arm that when the two parts are engaged the receptacle is held in upright position.

Upon the top board 79 of the machine, joining the apices of the end frames I mount a clothes wringer 80 of usual construction having one of its roller shafts 80' extend through a bearing block 81 carried by said board. On said shaft 80' I mount two opposed beveled gears 81' and 83 rotatable on the shaft, and between said gears I provide an idler pinion 84 mounted on the block 82 to communicate motion from one gear to the other. To the gear 82 I connect a sprocket 85, receiving power through chain 86 from sprocket 62. Each of the opposed gears 82 and 83 has its hub shaped to constitute a clutch member and between said opposing hub clutch I provide a central longitudinally shiftable clutch member 87 splined to the shaft 80'. A central groove 88 of said shiftable clutch member is engaged by a spiral blade 89 of an operating lever 90, pivoted in arms of the bearing member 82. For latching the clutch shifting blade 89 in any of its three positions I mount a round ended latch pin 93 in the recess 94 of the hub of the lever 90 and arrange a spring 95 to press said latch pin outward so that it may engage any one of a series of holes 96 made in the side wall of its bearing frame.

While I have herein described in some detail a specific embodiment of my invention it will be apparent to those skilled in the art that many changes in details of construction

might be made without departure from the spirit of my invention and within the scope of the appended claims.

What I claim is:—

1. In a device of the character described, a frame; a part to be driven at will mounted therein; a power appliance adapted to be constantly run; means, including a clutch movable "in" and "out", to operatively connect and to disconnect said part-to-be-driven and the power appliance; clutch-shifting means; and a latch for holding said part-to-be-driven at rest, coöperating also with the clutch-shifting means, said latch restrained by the clutch-shifting means against movement to latching position when the clutch-shifting means is in clutch- "in" position, and said latch when in latching position restraining said clutch-shifting means against movement to clutch- "in" position. 75

2. In a device of the character described, a frame; a part to be oscillated at will mounted therein; a power appliance for moving it adapted to be constantly run; means, including a clutch movable "in" 90 and "out" operatively to connect and to disconnect, respectively, said oscillatable part and the power appliance; a clutch-shifting lever; and an oscillating latch coöperating with said oscillatable part and said clutch-shifting lever, and having parts to simultaneously lock said lever in clutch- "out" position and the oscillatable part in stationary position, said latch restrained by said clutch-shifting lever against movement 100 to locking position when the lever is in clutch- "in" position.

3. In a device of the character described, a frame; a part to be oscillated at will mounted therein; a power appliance for 105 moving it adapted to be run constantly; means including a clutch movable "in" and "out" operatively to connect and to disconnect, respectively, said oscillatable part and said power appliance; a clutch-shifting 110 lever; a latch-receiving part on said oscillatable part; an oscillatable latch carried by the frame, and disposed at an angle to the plane of movement of said latch-receiving part, said latch having a nose thrown into 115 or out of latching position by oscillation of the latch, means for coöperating with the lever, when the latter is in clutch- "out" position to prevent movement of said lever to clutch- "in" position; and means for coöperation with said lever to prevent movement of the latch to latching position when the lever is in clutch- "in" position. 120

4. In a device of the character described, a frame provided with brackets, a part to be oscillated, a plate secured upon each end thereof and provided with trunnions for engagement in said brackets to support said parts for oscillation in the frame, one of said plates provided with a radial arm, spring-

- engaging means upon the end of said arm, a lever pivoted on the trunnion, said lever being shorter than the arm of the plate, spring engaging means on the end of the lever, a laterally resilient spring secured between the arm and lever normally holding said arm and lever parallel, and means to oscillate the lever for oscillation of the oscillatable part through the agency of said spring.
5. In a device of the character described a part to be oscillated, a power driven element, and means to connect said part and power element comprising a shaft, clutch means to connect the shaft and power element, a lever pivoted coaxially with said part, a spring connected between the end of said lever and a point of said part spaced from the axis thereof, and connections between the lever and the shaft for oscillation of said part through the spring and lever, said connections including a yielding pitman.
10. 6. In a device of the character described a part to be oscillated, a power driven element, and means to connect said part and power element comprising a shaft, clutch means to connect said shaft and power element, a lever pivoted coaxially with the said part, a spring connected between the end of said lever and a point on said part spaced from the axis thereof, connections between the lever and shaft for oscillation of said part through the spring and lever, a yielding spring member, and coacting projections upon the shaft for frictional engagement of said spring when said part approaches either extreme of its oscillating movement.
15. 7. In a device of the character described a part to be oscillated, a power driven element, and means to connect said part and power element comprising a shaft, clutch means to connect the shaft and power element, a lever pivoted coaxially with said shaft, a spring connected between the end of said lever and a point on said shaft spaced from the axis thereof, connections between lever and shaft for oscillation of said part through the spring and lever, said connections including a yielding pitman, a yield-
- ing spring member, and coacting projections upon the shaft for frictional engagement of said spring when said part approaches either extreme.
8. In a device of the character described a part to be oscillated, a power driven element, and means to connect said part and power element comprising a lever pivoted coaxially with said part, a transversely resilient spring secured between the end of the lever and a point on said part spaced from the axis thereof, and means to oscillate the lever including a rotary part for connection to said power arm, cam projections thereon, and a spring frictionally engaged by said projections when said lever and said part approach the extreme of the oscillating movement.
10. 9. In a device of the character described, an oscillatable part to be driven; a rotatable main shaft; operating connections, including a crank, between said shaft and oscillatable part; and checking devices resisting movement of said crank over dead center.
15. 10. In a device of the character described, an oscillatable part to be driven; a rotatable main shaft having a crank; operating connections between said crank and the oscillatable part; cam projections carried by said shaft and a check spring acting on said cam projections as the crank passes dead center.
20. 11. In a device of the character described, an oscillatable part to be driven; a rotatable main shaft; operating connections between said main shaft and the oscillatable part, said connections including a crank on the main shaft and yielding connections to permit lost motion between the crank and the oscillatable part; and means operating on said main shaft to resist its movement at the points when the crank passes dead center.
25. In testimony whereof I hereunto set my hand in the presence of two witnesses.

CARL W. SWANSON.

In the presence of—

N. T. FOWLER,
ELSIE V. GERNERT.
